UNITED STATES PATENT OFFICE.

ALVIN E. BERLIN AND PARVIN WRIGHT, OF DENVER, COLORADO.

PACKING AND SALES CASE.

SPECIFICATION forming part of Letters Patent No. 407,918, dated July 30, 1889.

Application filed February 13, 1889. Serial No. 299,809. (Model.)

To all whom it may concern:

Be it known that we, ALVIN E. BERLIN and PARVIN WRIGHT, citizens of the United States, residing at Denver, Arapahoe county, Colorado, have invented certain Improvements in Boxes, of which the following is a specification.

The object of our invention is to provide a handy box for crackers, soap, dried fruits, &c., into which access can be had without tearing off the top or pulling out nails, and which enables the boxes to be piled one on top of the other, so as to economize space in retail houses and elsewhere. It is also provided with a detachable glass lid, which displays the contents and keeps out dust and dirt.

Figure 1 is a longitudinal section of our improved box or case. Fig. 2 is a front elevation thereof. Figs. 3, 4, and 5 are details thereof.

The invention is sufficiently illustrated in the diagram presented in the annexed drawings, forming part of this specification.

Fig. 1 shows the box with the door A in the end, or in the side, if preferred, which has guides B, of sheet-iron or any other suitable material, attached to the sides to prevent the contents from falling out when opened.

The top and bottom edges I are beveled, and when the door is closed said beveled edges fit corresponding beveled edges of the door-opening. When this box is packed with certain kinds of merchandise—such as oyster-crackers, tea, dried berries, &c.—it is necessary to have a supplemental folding door C, which, when closed, covers about one-half of the opening and prevents the contents from rolling out, and enables one to get a scoop in to remove part of the contents, after which the lever H, Fig. 2, is moved to one side and the folding door drops down on the outside door A. Fig. 1 also shows the detachable glass lid D opened, which works on a hinge and

may be removed when the box is empty and put onto a full box. This lid is held to the top edge of the door by a clamp-hinge or any other suitable hinge. Fig. 3 shows the box closed.

When the box is made, it is necessary to

stiffen the edge at the door, if made of thin lumber. Instead of nailing a cleat on the inside we bend a strip of metal longitudinally in U or L shape corners, either square or round, Fig. 4, and fasten it over the ends of 55 the boards. If the side is composed of two or more narrow strips it holds them together firm and stiff. A small hole is made in this metallic strip, through which to drive a nail into the door, which serves as a hinge. 60

Fig. 5 shows a view of the fastenings which hold the door closed. When handling or shipping, a hole is bored in the door A at E, into which a pin or bolt F slides, which has a recess S in it, and is held normally in a position shown by spiral spring G. K is a hole bored in the door for the reception of a ring L, which is attached to the bolt F. When the ring is in the hole, it is impossible to move the pin down; but when the ring is 70 pulled down it thus opens the box. When the door is closed and the ring is in its place, a seal is pasted over the hole, or a label is put over the entire end of the box, so that the ring cannot be moved without breaking the 75 seal or tearing the label. The recess S in the pin F is for the purpose of putting the end of the finger so that the ring can be more readily taken hold of.

We claim—

1. A show and sales case having an opening therein, a door pivoted in said opening, and sectors or cheek-pieces attached to the side frame of said door and extending within said case to serve as guards in the withdrawal of 85 its contents, substantially as described.

2. A show and sales case having a door pivoted in an opening therein, sectors or cheeks secured to the side edges of the said doors and extending within the case, and an 90 auxiliary door hinged to the outer edge of the main door and provided with a glass through which the contents of the case may be observed, substantially as described.

3. A show and sales case having a door 95 pivoted in an opening therein, sectors or cheeks secured to the sides thereof, an auxiliary door-frame hinged to the outer edge of the main door and having a glass through which the contents of the case may be ob- 100

served, a hinged flap located within the case to prevent the case overrunning of its contents, pivoted detent to bear against said flap to retain it in a vertical position, and a sliding bolt 5 on the main door, and a recess in said door for the bolt-ring, substantially as described.

4. A show and sales case having a door, a sliding bolt therein, a recess in said door, and a ring attached to the bolt and falling in said 10 recess to be protected by a sealing-sheet over

said opening to prevent the contents of the case being tampered with while in transit, substantially as described.

In testimony whereof we have hereunto subscribed our names.

ALVIN E. BERLIN.
PARVIN WRIGHT.
